WASHING MACHINE

Sidney S. Holland, Sandusky, Ohio, assignor, by direct and mesne assignments, to The Apex Electrical Manufacturing Company, Cleveland, Ohio, a corporation of Ohio

Application September 27, 1935, Serial No. 42,485

5 Claims. (Cl. 68—22)

The invention to be hereinafter described relates to washing machines.

Briefly it is a combination of demountable non-reversible wringer and insulated tub.

5 It has been common practice to secure the wringer on the tub in any one of a number of simple suitable ways. They are fixed to the washer as by bolting, riveting and the like. They are not demountable. They may not be easily and quickly 10 picked off or set in place. No provision is made against reversing them so that the drain board is in the wrong place, or otherwise incorrectly positioning the wringer on the tub. Washers, as heretofore made, have not been insulated. There 15 is a great and unnecessary heat loss. This unnecessarily overheats the room where the washer is and, of course, is uneconomical to that extent. Also, washers as at present constructed have a single-structure tub in which a single cylindrical 20 wall serves both as tub and as skirt flange or housing for the motor and operating parts beneath the tub bottom, all as is well understood. It is impossible to separate tub and housing in case of injury to either.

25 The present invention eliminates the above and other objections and provides a simple, efficient, compact and economical machine in which the wringer is quickly and easily demountable and cannot be improperly positioned. It also provides 30 an insulated removable tub of great simplicity and very low cost production.

In order to more clearly disclose the construction, operation and use of the invention, reference should be had to the accompanying drawings 35 forming part of the present application. Throughout the several views like reference characters designate the same parts.

In the drawings—

40 Fig. 1 is a side elevation, with tub, spider and agitator sleeve shown dotted;

Fig. 2 is a top plan view of Fig. 1, enlarged;

Fig. 3 is an enlarged vertical cross section on line 3—3 of Fig. 1, through one-half of the machine;

45 Fig. 4 is an end view of wringer from the handle side;

Fig. 5 is an enlarged cross section on line 5—5 of Fig. 1.

Referring to the drawings in detail, 1 indicates a cylindrical metal shell adapted to contain the tub and all working parts. Heretofore, the tub has been built in or otherwise made integral with this shell. In the present invention that is not the case. At a point in the length 50 of the shell corresponding to the depth of the

tub is secured a spider, disc or other suitable support 2. For ready assembly, this spider is provided with attaching flanges 3 by which it may be readily and securely but detachably connected to shell 1 as by bolt and nuts 4 and 5. With the spider secured in place, a solid support for the tub and its load is provided. In this invention a tub 6, separate and independent of the shell 1 is provided. Tub 6 is of appreciably less cross sectional area than the interior of shell 1. When it is arranged in operative concentric position relative to shell 1 the assembly provides a peripheral air chamber in which the air is still or dead as it has no outside communication. As is well known, noncirculating or still air is the 10 most efficient thermal or heat insulator practical. By this construction, the tub is thoroughly insulated throughout the entire extent of its side walls. This of course reduces heat loss in washing and, at the same time, avoids undesirable overheating in the room, where the washer is used. Tub 6 is provided with a peripheral roll flange 7 completely bridging and closing the upper end of the air space and resting on the upper edge of shell 1. In order to retain tub 6 concentric with shell 1 and maintain uniform width of air chamber or spacing between shell 1 and tub 6, a centering opening is provided through the center of the bottom of the tub. A corresponding opening is provided through spider 2 and is strengthened by a hub 8. Hub 8 is interiorly threaded to receive a threaded extension 9 on a stationary tubular agitator post or sleeve 10. This post has a broad shoulder 11 concentric with the extension 9 and adapted to clamp the adjacent tub bottom between it and the spider 2, as will be readily understood. To make a water tight seal and prevent leakage from the tub into the machinery, a gasket 12 is provided and is clamped between shoulder 11 and the tub bottom. In assembling, the tub is placed in position so that the hole through its bottom is concentric with the hub 8. Then the extension 9 of the post 10 is threaded into the hub 8 until shoulder 11 securely clamps the tub bottom to the spider 2. 45 This pulls the tub 6 down to tight seating of roll flange 7 against upper edge of the wall of shell 1, completely sealing the insulating air space or chamber. At the same time, this coupling or connection correctly centers the tub to maintain uniform width of the air chamber or space between shell 1 and tub 6. It is obvious that the tub may be quickly and easily removed and replaced whenever desired.

Preferably a bead 13 is provided on the inner 55

the cover and portions 34 and makes it possible to slide the cover to and from closing position without interference.

By having the wringer mounting at one side 5 of the center the cover knob is readily accessible and the cover may be easily lifted and taken out from the other side practically as readily as though the wringer were not in place.

There is a great and rapidly growing field in 10 apartments, flats and single rooms, for small, compact washers which may be readily stored or rolled away into otherwise waste space and as easily rolled out again for use. A space-saving type where all space is at a premium. The present invention meets fully and quickly all such requirements. When not in use the wringer, 15 complete, is simply lifted off, the washer set under the sink where it will have plenty of room and will occupy only space otherwise entirely waste. The wringer with drain board and handle disconnected may be set right alongside. It is, of 20 course, only necessary to turn out the screws of the drain board and loosen the set screw of the handle in order to disconnect them. And when 25 the wringer is again desired it is only necessary to assemble the drain board and handle and again set the wringer in place.

From the above it will be seen that gravity 30 alone actuates the means for maintaining the wringer in operative position with the feet 32 in the cooperating sockets 33 and the wringer upright above the tub but to one side of its center.

The construction, operation and use of the invention will be clear from the preceding detailed 35 description.

Many changes may be made in the construction, arrangement and disposition of the various parts of the invention, within the scope of the appended claims without in any degree departing 40 from the field of the invention and it is meant to include all such within this application wherein only one preferred form has been illustrated, purely as an example and with no intent to limit in any degree the scope of the claims.

Having thus described my invention, what I 45 claim and desire to protect by Letters Patent is:

1. In combination, a washing machine having a cylindrical upper wall, a wringer provided with feet spaced apart a distance less than the outside diameter of said cylindrical wall and of the same curvature as said wall, a drain board carried by said wringer and normally extending outwardly relatively to the centre of the machine, and sockets carried by said wall constructed to 50 support said feet in contact with said wall and removably support said wringer.

2. In combination, a washing machine having a cylindrical upper wall, a closure covering substantially the entire top, a wringer extending

across and above said wall and closure and provided with feet spaced apart a distance less than the outside diameter of said wall, said feet having inclined or tapered vertical edges, a drain board carried by said wringer and normally extending outwardly relatively to the centre of the machine, 5 said wall having sockets constructed to support said feet in contact with said wall and provided with walls of a taper corresponding to that of the aforesaid feet and removably supporting said 10 wringer in position.

3. In combination, a washing machine having a metal tub circular in cross section, a wringer having a pair of depending supporting feet spaced apart a distance less than the diameter of said tub, a pair of wringer supporting members carried by the side walls of said tub at one side of the vertical axis thereof and spaced from each other a distance corresponding to the distance between said feet, said feet and their respective supporting members having complementary interfitting parts, one of said feet and its supporting member diverging laterally with respect to the other foot and its respective supporting member, to preclude an end-to-end reversal of the wringer 25 with respect to the washing machine tub.

4. In combination, a washing machine having a circular tub, a wringer having a pair of depending supporting feet spaced apart a distance less than the diameter of said tub, a pair of wringer supporting members fixed to the side walls of said tub adjacent the top at one side of the vertical axis of the tub and spaced from each other a distance corresponding to the distance between said feet, said members forming with the wall of the tub laterally diverging pockets, said feet formed with a corresponding divergence to prevent an end-to-end reversal of the wringer with respect to the tub.

5. In a washing machine, a circular metal tub, 40 a wringer for said machine provided with a pair of depending feet spaced apart a distance less than the diameter of said tub, means to detachably mount the wringer on the tub, comprising a pair of members carried by the side walls of the tub spaced from each other a distance corresponding to the distance between said feet, said members each having a portion spaced from the side walls of the tub to form therewith pockets substantially parallel to the wall of the tub, said pockets diverging from each other horizontally and the width of said pockets being varied in a vertical direction, said feet shaped to provide a divergence corresponding to their respective pockets and their width being varied in a vertical direction to limit the vertical movement of the feet into the pockets and prevent an end-to-end reversal of the wringer with respect to the tub.
